Attorney

UNITED STATES PATENT OFFICE.

CHARLES A. BEGGS, OF RICE LAKE, WISCONSIN.

HOT-AIR FURNACE.

1,414,395.

Specification of Letters Patent.

Patented May 2, 1922.

Application filed September 1, 1921. Serial No. 497,595.

To all whom it may concern:

Be it known that I, CHARLES A. BEGGS, a citizen of the United States, residing at Rice Lake, in the county of Barron and State of Wisconsin, have invented certain new and useful Improvements in Hot-Air Furnaces; and I do hereby declare the following to be a full, clear, and exact description of the invention, such as will enable others skilled in the art to which it appertains to make and use the same.

The invention relates to heating appliances and more particularly to furnaces for supplying hot air and embodying a plurality of casings surrounding the fire pot.

The present invention provides a hot air furnace having a direct draft and a circuitous passage for the smoke and gases and concentric hollow casings included in the circuitous smoke and gas passage, whereby a maximum amount of heat is available for effective service in heating.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a vertical central section of a hot air furnace of the pipeless type embodying the invention,

Figure 2 is a diagrammatic section on the line 2—2 of Figure 1, and

Figure 3 is a diagrammatic section on the line 3—3 of Figure 1.

Corresponding and like parts are referred to in the following description and designated in the several views of the drawings by like reference characters.

The hot air furnace disclosed embodies a cast metal base 1 and a register 2. The body of the furnace is mounted centrally upon the base 1 and comprises an ash pit 3 and a combined fire pot and combustion chamber 4. These parts may be of any approved construction. The outermost casing comprises a cylindrical portion 5, mounted upon the outer portion of the base 1, a conical or tapering portion 6 and an upper contracted

cylindrical portion 7 connected with the outer portion of the register 2. This outer casing is single and preferably formed of sheet metal such as galvanized iron. A hollow casing 8 surrounds the combined fire pot and combustion chamber 4 and is in communication at its upper end with the upper end of the part 4 by means of a plurality of short radiating tubes 9. A second hollow casing surrounds the hollow casing 8 and conforms to the outermost casing and comprises a cylindrical portion 10, a conical or tapering portion 11 and an upper contracted cylindrical portion 12. The cylindrical portion 10 is disposed in the space between the casing 8 and the part 5 of the outermost casing and is in communication at its lower end with the lower portion of the casing 8 by means of short radiating tubes 13. The parts 11 and 12 are disposed in the space above the part 4 and conform to the parts 6 and 7 of the outermost casing. A smoke pipe 14 connects with the upper part 12 of the outer hollow casing and is provided with a damper 15. A smoke pipe 16 connects with the upper portion of the inner hollow casing 8 and is provided with a closely fitting damper 17. The top of the outer casing connects with the register 2. When the furnace is of the pipeless variety as indicated in the drawings, the cold air passes through the outer portion of the register 2 into the cold air space formed between the outermost casing and the outer hollow casing and the hot air escapes through the central portion of the register after being heated in its passage through the spaces formed between the hollow casing and the body of the furnace.

When a direct draft is required to cause the fire to burn briskly or when starting the furnace, the valve 17 is opened thereby providing a direct escape for the smoke and products of combustion. After the fire has attained the desired headway, the damper 17 is closed thereby compelling the products of combustion to travel in a circuitous passage represented by the parts 9, 8, 13, 10, 11 and 12.

The walls of the combined fire pot and combustion chamber and the hollow casing and the pipe connections 9 and 13 present a large area of heating surface for warming the air passing thereover or adjacent thereto. It will thus be understood that a relatively high percentage of the heat developed

by the consumption of the fuel is utilized for heating purposes. The structure is simple and compact and the spaces between the heating surfaces may be of such extent 5 as to obtain the best results the utilization of the heat develops. While the furnace illustrated is of the pipeless type it is to be understood that the invention is equally well adapted for furnaces provided with 10 hot air distributing pipes which may be connected with the hot air space in the upper portion of the surrounding casing. The fuel and ash pit doors and the snouts or connections associated therewith have been omitted 15 from the accompanying drawings for the sake of simplicity of illustration and furthermore because such parts are well known in the art and form no part of the present invention.

20 Having thus described my invention what I claim is:—

1. A hot air furnace comprising a body including a fire pot and combustion chamber, a hollow casing surrounding said body, 25 short pipes radiating from the upper portion of the body and connecting the same with the upper portion of the hollow casing, a second hollow casing surrounding the primary hollow casing, short radiating pipes 30 connecting the lower portions of the primary and secondary hollow casings, a smoke pipe connected with the upper portion of

the primary casing and provided in its length with a close fitting damper and a second smoke pipe connected with the upper portion of the second hollow casing and having a damper in its length. 35

2. A hot air furnace comprising a body including a fire pot and combustion chamber, an outer casing enclosing the body and comprising a lower cylindrical portion, an intermediate tapered portion and an upper contracted cylindrical portion, a primary hollow casing surrounding the body, short radiating pipes connecting the upper portions of the body and primary hollow casing, a smoke pipe leading from the upper portion of the primary casing and provided in its length with a close fitting damper, a secondary hollow casing comprising a lower cylindrical portion, an intermediate tapered portion, and an upper contracted cylindrical portion, a smoke pipe leading from the upper portion of the secondary casing and provided in its length with a damper, and short radiating pipes connecting the lower portions of the primary and secondary hollow casings. 45 50 55

In testimony whereof I affix my signature in presence of two witnesses.

CHARLES A. BEGGS.
